Attorney

UNITED STATES PATENT OFFICE.

WILLIAM F. SHAW, OF DENVER, COLORADO.

HANDPIECE.

1,354,139.

Specification of Letters Patent. Patented Sept. 28, 1920.

Application filed July 2, 1920. Serial No. 393,504.

To all whom it may concern:

Be it known that I, WILLIAM F. SHAW, a citizen of the United States, residing at Denver, in the county of Denver and State 5 of Colorado, have invented a new and useful Handpiece, of which the following is a specification.

One object of this invention is to provide novel means whereby reciprocating movement may be imparted, from a rotatable shaft to a tool holder disposed at an angle 10 to the shaft.

Another object of the invention is to provide a novel tool adapted for use on a device 15 of the sort above set forth.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention.

In the accompanying drawings:—

Figure 1 shows in longitudinal section, a device constructed in accordance with the invention; Fig. 2 is a cross section on the line 2—2 of Fig. 1; Fig. 3 is a cross section on the line 3—3 of Fig. 1; Fig. 4 is a perspective view showing one form of tool adapted to be used with the device disclosed in Fig. 1; Fig. 5 is a plan showing another form of tool adapted to be used in 40 connection with the tool shown in Fig. 1; Fig. 6 is a cross section on the line 6—6 of Fig. 5; Fig. 7 is a cross section on the line 7—7 of Fig. 5; Fig. 8 is a longitudinal section on the line 8—8 of Fig. 5.

In carrying out the invention there is provided a holder, denoted generally by the numeral 1, the holder comprising a hollow rear end 2, a hollow forward end 3 and an intermediate bearing 4, the end 2 of the holder being adapted in any suitable way, as indicated at 5 for connection with a dental engine. The end 3 of the holder 1 is provided with an outwardly projecting boss, a slot 7 being fashioned in the extremity of 55 the end 3. A cap 8 is mounted on the end 3 of the holder 1 and is provided with an

opening 9 adapted to receive the boss 6 on the end 3, to hold the cap detachably on the member 1, the end 3 of the holder having enough resiliency to enable the boss 6 to enter the opening 9 and to be detached from the opening, upon the application of sufficient pressure. The cap 8 has a side aperture 10 alined with the slot 6 in the end 3 of the holder 1.

A shaft 11 is journaled for rotation in the intermediate bearing 4 and extends into the hollow ends 2 and 3 of the holder 1. Within the end 3 of the holder, the shaft 11 is supplied with an abutment 12, which may be in 70 the form of a collar. At its forward end, the shaft 11 is reduced in diameter to form a spindle 14.

A resilient U-shaped tool carrier is provided, the same including a rear arm 15, a 75 forward arm 16 and an intermediate portion 17 connecting the arms 15 and 16. The arm 15 is engaged about the shaft 11 to the rear of the abutment 12 and preferably in contact therewith, the spindle 14 of the shaft 80 being rotatably received in the arm 16 of the tool carrier. Adjacent to the abutment 12, the shaft 11 is bent at an obtuse angle to form a crank 18. The arm 16 of the tool carrier is disposed at right angles to the 85 shaft 11 and is mounted to reciprocate in the slot 7 of the end 3 and in the aperture 10 of the cap 8. The arm 16 terminates in a reduced finger 19 defining a shoulder 20.

It will be clear that when rotation is imparted to the shaft, a right line reciprocation will be imparted to the arm 16 of the carrier, owing to the presence of the crank 18.

Passing to Fig. 4, there is shown a tool including a resilient split sleeve 21 and a 95 body 22 which may have a file surface 23, or a surface of any other kind, depending on the nature of the work in hand. The finger 19 is received with the slit resilient sleeve 21, the sleeve abutting against the 100 shoulder 20. The tool is held on the finger 19 in such a way that the tool may be rotated, thereby to dispose the body 22 of the tool properly, with respect to the surface which is to be worked upon.

In Figs. 5, 6, 7 and 8 there is shown a tool including a body 24 and a split resilient sleeve. One end of the body 24 is supplied with a resilient tongue 26 extended forwardly within the sleeve 25. The body 24 is provided at its sides with arms 27 overhanging the tongue 26 and engaging the

same, the arms serving to strengthen and reinforce the tongue. A strip of abrasive material indicated at 28, may be thrust beneath the tongue 26. When the finger 19 is inserted into the sleeve 25, the finger will flex the tongue 26 and press the same firmly against the strip 28, the strip thus being held in place on the body 24.

Having thus described the invention, what is claimed is:

- 10 1. In a device of the class described, a holder; a shaft journaled in the holder and provided with a crank; and a U-shaped tool carrier comprising arms, one of which is mounted on the shaft, the other of which is mounted on the crank.

2. In a device of the class described, a holder; a shaft journaled in the holder, the shaft being obtusely bent to form a crank, and being provided with an abutment at the 20 inner end of the crank; and a resilient U-shaped tool carrier comprising arms, one of which is engaged with the extremity of the crank, the other of which is engaged with the shaft to the rear of the abutment. 25

In testimony that I claim the foregoing as my own, I have hereto affixed my signature in the presence of two witnesses.

WILLIAM F. SHAW.
